PIZZA

Charles Silvestri, 280 85th St., Brooklyn, N.Y. 11209

Filed Oct. 31, 1972, Ser. No. 302,568

Term of patent 14 years

Int. Cl. D1—01

U.S. Cl. D1—11

FIG. 1

FIG. 2

FIG. 1 is a top view of a pizza embodying my new design;

FIG. 2 is a side view thereof; and

FIG. 3 is a fragmentary sectional view thereof taken on line 3—3 of FIG. 2 on an enlarged scale.

The pizza is characterized by having an enlarged peripheral crust with large crystals of salt embedded therein.

I claim:

The ornamental design for a pizza, as shown and described.
